UNITED STATES PATENT OFFICE

EMIL GATHMANN, OF BALTIMORE, MARYLAND

INGOT MOLD AND INGOT

Application filed April 3, 1929. Serial No. 352,277.

This invention relates to the casting of metallic ingots and involves certain improvements in the contour and proportional dimensions of the horizontal cross section of the 5 vertically-extending mold chamber and of the ingot formed therein.

More especially my present invention relates to improvements in the form of mold chambers and ingots shown, described, and 10 claimed in my U. S. Patents No. 1,440,535, of January 2, 1923, No. 1,484,940, of February 26, 1924, No. 1,532,741, of April 7, 1925, and in my co-pending application, Serial No. 315,523, filed October 27, 1928.

15 As is now well known to those familiar with the art, an ingot cast in a vertical mold having a uniformly corrugated dodecagon of twelve-sided cross sectional chamber contour is subject to the formation of fewer surface 20 flaws or defects during solidification than any other form of ingot heretofore known. An ingot of this type, however, in common with other ingots of substantially round or of oval cross section, is more or less difficult to handle 25 in the rolling mill; and, if properly reduced, requires a greater number of initial mill passes than are necessary in the reduction of a substantially rectangular ingot of the same maximum cross sectional dimension in order 30 to insure against tearing of the outer structure or skin of the ingot, both at the primary faces thereof and at the corner portions.

By my present invention I obtain the advantages in surface solidification characteristic 35 of ingots of the kind having a dodecagon cross section, at the same time retaining the advantages of an ingot of rectangular cross section in reduction of the ingot in the rolling mill.

40 As is now well known to those familiar with the art, a steel ingot, irrespective of its physical condition or chemical analysis, when stripped from the mold and placed in the soaking pit or reheating furnace, is merely 45 a surface-chilled casting; and until work is done upon all its surfaces in the reduction of the coarse-grained crystals, the ingot inevitably has the weakness inherent in castings as compared to forgings. The reduction of 50 the section of the ingot should, therefore, be

so accomplished that no unworked surface portion receives appreciable deformation in reduction or working of adjacent portions. In practice this has heretofore been best accomplished by making initial reduction passes 55 light, and by frequently turning the ingot. This frequent turning of the ingot has been an expensive procedure and by my improved contour I largely eliminate the necessity of frequent turnings and so-called babying or 60 light preliminary passes.

My improvements may be embodied in any type of vertical mold—big-end-up, big-end-down, or parallel chamber walls for the production of ingots with or without shrink head 65 portions.

In the accompanying drawings:

Figure 1 shows a vertical central section of an ingot mold of the big-end-up type provided with a shrink head casing constructed 70 in accordance with my invention, the plug for the bottom opening being shown in elevation and the stool in section.

Figure 2 is a side elevation of the exterior of a big-end-up mold embodying my improvements and of the kind shown in Figure 1.

Figure 3 is a view on an enlarged scale and in section on the line 3—3 of Figure 1.

Figure 4 is a view on an enlarged scale and in horizontal section of a quarter portion of 80 the mold shown in Figure 3.

Figure 5 is a perspective view of an ingot formed in a mold of the type shown in Figures 1, 2, and 3.

Figure 6 is a perspective view on an enlarged scale of the shrink head casing shown in Figure 1 for forming the upper part of the 85 ingot.

Figure 7 shows on an enlarged scale a cross section of the ingot shown in Figure 5.

The mold body A is preferably made of cast iron or other heat-absorbing metal of suitable character and rests on a stool B having a recess or trough B' of the type shown in my U. S. Patent No. 1,039,725, of October 1, 1912. The mold top or shrink head casing S is preferably made of refractory heat-conserving material.

The inner walls of the mold chamber are shown as vertically corrugated, both on the 100

primary walls and at their corner portions, as indicated at C and C', these corrugations producing salients D and D' of the type hereinafter described. In big-end-up mold designs, these corrugations preferably extend into the necked-in portion of the mold and merge or disappear therein, as shown in Figure 1, and as shown and claimed in my U. S. Patent No. 1,532,741, of April 7, 1925.

10 It should be borne in mind that three prime factors must be considered in designing the cross section of a mold in order that the best results may be obtained.

15 A. The ingot must be free to solidify without binding or hanging to the matrix walls of the mold and be allowed to contract inwardly with a minimum of surface stress.

20 B. The salients and corners of the matrix must be of such angular contour that the ingot formed in the mold will not easily become overheated and decarburize at its surface portion while in the soaking or reheating pits.

25 C. Each primary side of the ingot must be relatively narrow and extend in a plane sufficiently outwardly beyond the adjacent corner salient so that in the initial deformation in the rolls, the corner salients will not be unduly worked nor the adjacent unworked sides appreciably stressed.

30 I have also found that fewer shrinkage cracks occur in the surface of an ingot during its solidification and also during the mill reduction operation when certain definite angular and radial proportions of the corners and adjacent walls of the mold are employed; and my present invention relates especially to the horizontal contour and proportions defining the cross section of the ingot and the 40 chamber of the mold in which it is produced.

45 In Figures 1 and 2 of the drawings, lugs O and O' are shown as being cast integrally with the mold walls at the upper and lower portions thereof, whereby the mold may be lifted and manipulated as desired in setting up a "jag" and in removing the solidified ingots therefrom.

50 As shown in Figure 3, the inner walls defining the mold chamber comprise essentially four primary inwardly-bellied or corrugated side walls C, the walls of each oppositely-disposed pair being substantially parallel with each other or rather parallel with lines drawn across the vertexes at the end of the corrugations; in other words, the walls are so disposed that a tangent passing across the face of the vertexes of said walls will form an angle of 90° from the tangent passing across the vertexes of each adjacent primary side 55 wall. Eight inwardly-arched secondary corner walls C' are connected together in pairs by four relatively small outwardly-arched primary corner walls D, the secondary corner walls C' being in turn connected 60 to the inwardly-arched primary side walls C

by eight relatively small outwardly-arched wall portions D', which form the apexes of the primary side walls.

65 The width, or, more specifically, the chord of each of the primary walls C is preferably less than one third of the maximum horizontal cross sectional dimension of the ingot mold chamber, this width being designated by d in Figures 3 and 7.

70 Referring to Figure 4 of the drawings, which shows on an enlarged scale one quadrant of the mold illustrated in Figure 3, C—C indicate portions of the two adjacent primary side walls of inwardly bellied or arched contour, and R indicates the preferred length of 75 the radius describing each of the walls C, the length of each radius being greater than the width or chord of each of said walls. The inwardly arched secondary corner walls C' which connect the respective primary side 80 walls C to the adjacent corner walls D are preferably described about centers x—y by radii R'. Each of the centers x—y is located within a right angle L included between two lines L'—L' and L²—L² which intersect at the center p from which the adjacent corner wall D is described. The intersecting lines L'—L' and L²—L² are respectively parallel to neutral lines of peripheral shrinkage N—N' and N—N as shown in 85 Figure 4. It is important for the best contour of mold chamber that the radii R' be struck from centers located between the lines L'—L' and L²—L² or in proximity to these lines, as shown at x—y, which lines, as stated, 90 intersect at the centers p from which the primary corner walls D are described by the radii r.

95 The dotted lines T, which indicate the contour of an old type rectangular mold chamber, are parallel to the lines L'—L' and L²—L², which lines are located so as to intersect at an angle of 90° one with the other at or about the points p, from which the radii 100 describing the primary corner walls D are swung. Such a contour prevents the formation of reentrant angles at the junction of the secondary corner walls C' and the primary corner walls D. This is very important, as such reentrant angles would tend to 105 obstruct free contraction of the skin of the ingot during solidification within the mold and thus cause tearing of the ingot surface. It will be observed that the primary side walls C are connected to the adjacent corner walls C' by means of outwardly-extending salients D', and that each of these inwardly-bellied corner wall portions C' extends at an angle of from 5° to 15° to a tangent connecting the apexes of a pair of the salients D' 110 at the opposite ends of an adjacent primary side wall C, as illustrated in Figures 3, 4, and 7.

115 The arc defining the primary corner walls D subtends an angle of more than 45° and 120

the arc defining the wall D' subtends an angle of less than 45°.

The exterior contour of the mold V is preferably so designed that the walls of the mold chamber are of gradually lessened thickness from the primary side walls C through the secondary corner walls C', having a minimum thickness at the primary corners D, the corners forming the outer contour of the mold walls being shown as preferably described by radii r' about the centers p .

The employment of the beforementioned radii and angular proportions produces a contour of corrugated mold chamber which permits of free shrinkage during solidification of the outer skin or contacting portions of the solidifying ingot without danger of physical binding of said skin with the mold walls. The ingot produced in such a mold is of such contour that it may be reheated without danger of corner burning; and the surface of the ingot will be consolidate in rolling mill operations without material elongation of the ingot as a whole.

Furthermore, the thickness or heat-absorptive value of the mold is progressively decreased towards the primary corners so that a substantially uniform rate of heat abstraction from the entire mass of ingot metal is obtained.

Figures 5 and 7 illustrate graphically an ingot I formed in a mold chamber of the kind shown and described. The outer portion of the ingot consists of inwardly-bellied or arched primary side walls E, which are connected to inwardly-bellied or arched secondary corner walls E' by outwardly-curved arched portions or salients F, the secondary corner walls E' being connected by outwardly-arched primary corner walls G.

The ingot I as shown is of the big-end-up Gathmann type provided with a shrink head portion W, which preferably has a contour similar to that of the ingot body. It should be understood, however, that my improvements may be embodied not only in big-end-up but in any type of ingot, whether equipped with a shrink head portion or not.

Figure 6 illustrates the type of shrink head casing S that I preferably employ, the same having an inner and outer contour similar to the contour of the chamber of the mold body. The shrink head casing is preferably supported on top of the mold, as shown in Figure 1, so that a portion thereof extends below the top of the mold and into the mold chamber.

Unless extreme care is taken in rolling, and particularly light reduction passes are employed, the round corrugated ingot heretofore known to the art is frequently torn at the corners before any real work has been done towards reducing the relatively coarse and weak structure of the ingot as cast. By shortening the relative width of the primary

side walls E of the ingot I, the metal in the neutral axes N—N' of the ingot is initially compressed to a greater degree in a transverse direction than is the metal lying in adjacent planes, and thus lessens longitudinal flow, and the danger of transverse cracks occurring in the unworked portions of the ingot is greatly reduced. In the rolling of an ingot embodying my present improvements, the initial mill passes not only reduce the primary inwardly-bellied side walls E and the secondary corner walls E', but also the primary corner walls G, so that the entire surface of the coarse crystalline structure of the cast metal is worked and refined or reduced to a forged rectangular structure before any considerable elongation of the ingot has taken place. Tearing of the surface of the ingot due to elongation strains or checks of coarse unworked crystals is thus practically eliminated.

A mold made in accordance with my invention has approximately 18% to 20% greater volume for a given maximum dimension of ingot than has an ingot of dodecagon cross section such as is at present widely used, so that it is possible to materially increase the tonnage of blooms or billets that may be reduced to specific size in a given number of mill passes.

Another advantage obtained by the employment of my new cross sectional contour over the dodecagon corrugated contour resides in the lessened number of molds and shrink head casings required to contain a given charge of molten metal. Furthermore, because of the fewer openings of the ladle stopper necessary for pouring a given heat of steel, there is less liability of trouble, particularly from so-called running stoppers.

It is well known to those familiar with the art that the maximum cross section of an ingot is limited by the size of the rolling mill and the height of the ingot by the depth of the soaking pits in which it is to be treated preliminary to reduction. Hence the 20% increase in the mass of metal in my new ingot over the round corrugated ingot represents a very considerable economy. As stated, fewer molds and shrink head casings are necessary to take care of any given heat of steel, so that the tonnage of output for any given furnace charge is considerably increased, while the quality of the surface of the finished product is superior to that heretofore obtainable.

While each of the four side walls of the mold cavity is preferably of the contour shown, fairly good results are obtained when two of the side walls are of the contour indicated, the other side walls being of another suitable contour.

I claim as my invention:

1. An ingot mold having a generally rectangular chamber provided with at least two inwardly-arched oppositely disposed pri-

- mary side walls, and with outwardly arched corner walls, connecting said side walls, the radius describing the arc of each of the side walls being of greater length than the chord of said arc, said chord being approximately one third of the maximum width of the chamber, the mold walls diminishing in thickness from the primary side walls towards the outwardly arched corner walls. 70
- 10 2. An ingot mold having a generally rectangular chamber provided with four inwardly-arched oppositely disposed primary side walls, and with outwardly arched corner walls connecting said side walls, the radius describing the arc of each of the side walls being of greater length than the chord of said arc, said chord being less than one third of the maximum width of the said mold chamber, the mold walls diminishing in thickness from the primary side walls towards the outwardly arched corner walls. 75
- 15 3. An ingot mold having a generally rectangular chamber provided with four inwardly-arched relatively narrow primary side walls and four outwardly-arched primary corner walls merging with a plurality of secondary corner walls, which in turn merge with the primary side walls and extend at an angle of from 5° to 15° from said side walls, the thickness of the mold walls gradually decreasing from the primary sides towards the corners. 80
- 20 4. A metallic mold having a generally rectangular ingot-forming chamber provided with four inwardly-bellied primary side walls, the radius forming the inwardly-bellied contour of each of said walls being of greater length than the width of each of said primary side walls, and four widened corners, 85 which are connected to the primary side walls by inwardly-bellied secondary walls, the radius of each of which is greater than the width of one of said primary walls, the thickness of the mold walls gradually decreasing from the primary sides towards the corners. 90
- 25 5. A metallic mold having a generally rectangular ingot-forming chamber provided with four inwardly-curved primary side walls, and four outwardly arched corner walls connecting the side walls, the radius describing the inwardly-curved contour of each of said side walls being of greater length than the width of an adjacent primary side wall, the mold walls diminishing in thickness 95 from the primary side walls towards the outwardly arched corner walls. 100
- 30 6. A metallic ingot having a generally rectangular cross section, at least two of the oppositely-disposed primary sides of which are of inwardly-arched contour, the radius describing the arc of each of said sides being of a length greater than the chord of said arc and the chord being less than one third of the width of the maximum cross section 105 of the ingot. 110
- 35 7. A metallic ingot having four inwardly-bellied primary side walls, the width of each of which is less than one third of the maximum cross sectional dimension of the ingot, and four outwardly-arched corner walls connected to the said primary walls by inwardly-curved walls each of which extends at an angle of from 5° to 15° from the adjacent primary side wall. 115
- 40 8. A metallic ingot having a generally rectangular cross section with four inwardly-arched sides, the radius describing the arc of each of said sides being of a length greater than the chord of the arc of an arched side and the chord being less than one third of the width of the maximum cross section of the ingot. 120
- 45 In testimony whereof, I have hereunto subscribed my name. 125
- EMIL GATHMANN. 130
